(57) **CLAIM**

The ornamental design for a tire traction device for tires, as shown and described.

DESCRIPTION

FIG. 1 is a perspective view of the traction device for a tire, partially disengaged;

FIG. 2 is a side view of a traction device for a tire, entirely disengaged;

FIG. 3 is a side view of a traction device for a tire;

FIG. 4 is a cross-sectional, cut-away enlarged detail from the side perspective of the traction device for a tire; and,

FIG. 5 is a side view of a traction device for a tire demonstrating the device entirely engaged upon a tire shown in broken lines.

In the drawings, the broken lines defining the tire in FIG. 5 depict environmental subject matter that forms no part of the claimed design.
